GARMENT

Louis A. Siegel, Mount Vernon, N. Y.

Application May 13, 1941, Serial No. 393,150

5 Claims. (Cl. 2—93)

The present invention relates to linings and more particularly to sleeved linings which may be removably secured within an outer garment so as to permit the use of such garment under varying climatic conditions.

It is the main object of the present invention to provide a garment of the general character indicated in which the removable lining is so constructed that elasticity is provided across the back, chest, shoulders, thus giving to the wearer more freedom of movement than has heretofore been possible in garments of this general nature.

It is another object of this invention to provide a garment lining wherein the sleeves are separated from the main body portion of the lining by the interposition of stretchable material and thereby enabling the attainment of the above mentioned primary object with greater facility than has heretofore been possible.

In the accompanying specification there shall be described and in the annexed drawing shown an illustrative embodiment of the detachable sleeved lining of the present invention. It is, however, to be clearly understood that the present invention is not limited to the exact details of construction herein shown and described for purposes of illustration only, inasmuch as changes in the details may be made therein without the exercise of invention and within the scope of the claims hereto appended.

In the accompanying drawing,

Figure 1 is a front elevational view of a portion of a detachable sleeved lining made in accordance with the principles of the present invention.

Figure 2 is a rear elevational view of the same partly broken away to show the inner construction, and

Figure 3 is an enlarged transverse sectional view taken along line 3—3 of Figure 1; and

Figure 4 is a front elevational view of a conventional outer garment provided with a detachable sleeved lining made in accordance with the present invention, the outer garment being turned back to more clearly show the lining.

Referring now more in detail to the aforesaid illustrative embodiment of the present invention, and with particular reference to the drawing illustrating the same, numeral 5 generally designates an outer garment, such as an overcoat, which is provided with a sleeved lining 6, which may be detachably secured therein by means of conventional hookless fasteners 7.

The detachable lining 6, which is made of non-stretchable material, comprises generally a back

portion 8, front portions 9, and sleeves 10. If desired, the sleeves 10 may be made of stretchable material, such as Lastex etc. instead of cloth or other non-stretchable material. The back portion 8, at the upper part thereof, in other words, between the shoulder blades, is provided with vertically disposed pleats 11 which enable lateral expansion in the back portion 8.

Along a line of stitching 12, the back portion 8 is secured to the back portion 13 of a vest-like member 14 made of stretchable material, the vest-like member also including front portions 15. The back portion 13 and the front portions 15 of the vest-like member 14, may be made of one piece or, if desired, may be made of separate pieces stitched along lines 16. Also, if desired, the stretchable material of the back portion 13 may be eliminated intermediate the rows of stitching 12.

20 The upper corners of the lining 6 are cut away so as to provide oversized armholes 17 and extending through these oversized armholes 17, so as to be exposed to view, are marginal areas 18, preferably integral with the back and front portions of the vest-like member 14, these areas extending completely about the armhole regions of the lining 6. The marginal areas 18 are provided with conventional armholes 19 to which are attached, by rows of stitching 20, the sleeves 10.

25 The lining 6 is itself provided with a lining which includes a back portion 21 provided with a fold 22, which enables lateral expansion of the back portion of the lining, this lining being secured to the sleeves 10 and the back portion 13 of the vest-like member 14 by the rows of stitching 20. The front portions 23 of this innermost lining are likewise secured to the sleeves 10 and also to the front portions 15 of the vest-like member 14 through the rows of stitching 20, and the outer edges of the front portions 23 of this lining are secured by rows of stitching 24 to the outer edges of the front portions 15 of the vest-like member 14 and to the outer edges of the front portions 9 of the lining 6. The same rows 24 of stitching also secure in place a stringer 25 which carries the hookless fastener elements 7. The garment is completed by providing the front portions 23 of the lining 6, intermediate the inner and outer edges thereof with folds 26 directed toward the stringer 25 to facilitate lateral expansion across the chest of the wearer, and securing the front portions 9 of the lining 6 to the front portions 15 of the vest-like member 14 along the rows of stitching 27.

This completes the description of the aforesaid illustrative embodiment of the present invention. It will be noted that, in its broad aspect, the invention consists of a coat-like garment lining in which there is secured a vest-like member, which vest-like member is provided with marginal areas extending through oversized armholes provided in the lining; the marginal areas being provided with conventional armholes, to which are secured the sleeves of the lining. The 10 garment lining is made of non-stretchable material, but the vest-like member secured therein is made of stretchable material. By this construction, there is provided a garment lining having elastic areas which permit complete freedom 15 of the chest, shoulders, and the back of the wearer.

Other objects and advantages of the detachable sleeved lining of the present invention will be obvious to those skilled in the art to which 20 the present invention relates.

What I claim as my invention is:

1. A garment comprising a coat-like member of non-stretchable material provided with oversized armholes, a vest-like member of stretchable material secured within said coat-like member and having portions thereof extending through and beyond said oversized armholes, said 25 extending portions of said vest-like member being provided with conventional armholes, and sleeves secured to said extending portions of said vest-like member at the armholes thereof.

2. A garment comprising a coat-like member of non-stretchable material provided with oversized armholes, means associated with said coat-like member to permit lateral expansion thereof, a vest-like member of stretchable material secured within said coat-like member and having 30 portions thereof extending through and beyond

said oversized armholes, said extending portions of said vest-like member being provided with conventional armholes, and sleeves secured to said extending portions of said vest-like member at the armholes thereof.

3. A garment comprising a coat-like member of non-stretchable material provided with oversized armholes, said non-stretchable material being provided with a pleated portion to permit lateral expansion thereof, a vest-like member of stretchable material secured within said coat-like member and having portions thereof extending through and beyond said oversized armholes, said extending portions of said vest-like member being provided with conventional armholes, and sleeves secured to said extending portions of said vest-like member at the armholes thereof.

4. A garment comprising a coat-like member of non-stretchable material provided with oversized armholes, a vest-like member of stretchable material secured within said coat-like member and having portions thereof extending through said oversized armholes to present exposed marginal areas throughout the entire armhole region of the garment, said exposed marginal areas of said vest-like member being provided with conventional armholes, and sleeves secured to said exposed marginal areas of said vest-like member at the armholes thereof.

5. A garment comprising a coat-like member of non-stretchable material, the portion immediately adjacent to and surrounding the armholes thereof being cut away to form oversized armholes; sleeves; and a strip of stretchable material coextensive with and attached to the oversized armholes of said coat-like member and provided with conventional armholes to which are attached said sleeves.

LOUIS A. SIEGEL.
